UNITED STATES PATENT OFFICE.

JULIUS J. MILLER, OF ST. JOSEPH, MICHIGAN, ASSIGNOR TO WILLIAM P. HEALY, OF CHICAGO, ILLINOIS.

BOX-BLANK MACHINE.

1,089,069.

Specification of Letters Patent. Patented Mar. 3, 1914.

Application filed October 11, 1909. Serial No. 522,156.

To all whom it may concern:

Be it known that I, JULIUS J. MILLER, a citizen of the United States of America, and resident of St. Joseph, Berrien county, Michigan, have invented a certain new and useful Improvement in Box-Blank Machines, of which the following is a specification.

My invention relates more particularly to machines for producing foldable wirebound box blanks of that character in which separate cleats and side-sheets are assembled as separate side sections, the operation of the machine including the introduction of these separate side sections in succession to wire attaching mechanism which binds one section to the next, so that the immediate result or product of the wiring operation is a box blank composed of a series of separate box-sides unconnected except by the wires. A machine of this character preferably has means for maintaining the cleats and side-sheets in such relation that adjacent edges of the sections mate properly when the blank is folded into box form.

Generally stated, and among other objects, this invention is intended to solve many of the problems involved in the proper connecting together of box parts such as those described and in maintaining the proper relative positions thereof, during the wiring operation, to insure their being foldable into desired relation at the points in the blank which form the box corners.

More specifically considered, however, the invention, in one form thereof, relates to machines of that type in which the construction and mode of operation admit of the feeding of cleats of different lengths without adjusting or changing the machine, and without necessarily stopping the continuous running thereof, when box blanks or sections of different lengths are desired; and contemplates the provision in a machine of this kind of novel and improved mechanism for feeding and positioning the parts of the box blank, whereby the cleats and sheets are secured together in proper relation.

Generally stated, the object of my invention is the provision of an improved and highly efficient machine for making wire bound box blanks of the foregoing character.

To the foregoing and other useful ends

my invention consists in the matters herein- 55 after set forth and claimed.

In the accompanying drawings, Figure 1 is a longitudinal section of a machine embodying the principles of my invention, showing certain parts broken away for convenience of illustration; Fig. 2 is a vertical section on line 2—2 in Fig. 1; Fig. 3 is an enlarged vertical section on line 3—3 in Fig. 1; Fig. 4 is an enlarged perspective of one of the links employed in the endless 60 link belt shown in Fig. 1; Fig. 5 is an enlarged perspective of one of the loose spacing blocks employed with the link belt shown in said Fig. 1; Fig. 6 is an enlarged detail view of a portion of the mechanism 65 for insuring a proper positioning of the cleats of the blanks, which mechanism is indicated at the extreme left in Fig. 1; Fig. 7 is an enlarged detail sectional view of a portion of said mechanism; Fig. 8 is a perspective of the pin or positioning device or finger shown in Fig. 7, there being one of these pins for each of the two cleat guides shown in Fig. 1, which pins are embodied 70 in the said mechanism for insuring a proper 75 positioning of the cleats of the blanks, whereby the cleats at one side of the blank, when the mechanism shown in Fig. 1 is used, are positioned exactly opposite the cleats at the other side of the blank; Fig. 85 9 is a perspective of one of the wire bound box blanks.

As thus illustrated, my invention comprises a suitable frame or body A, upon which are mounted certain of the operative 90 parts, said frame or body consisting of an upright casting at each side of the machine. The upright castings B are disposed a suitable distance in advance of the castings from which the frame A is constructed, and 95 are made preferably adjustable in any suitable manner whereby the distance between the castings A and B may be varied at will.

The frame A has a horizontal and transverse shaft C, and the castings B are connected by a shaft D, the shaft C having two sprockets E, and the shaft D having two similar sprockets F. A feed mechanism G has a pawl g that engages a ratchet g' on the shaft C, which pawl is on an arm g² that 100 swings on said shaft. This arm is connected by a rod g³ with the lever g⁴, which latter is operated by the usual cam mecha-

nism (not shown) at the lower portion of the machine. A spring g^5 is applied for re-tracting the rod g^3 , in the well known manner. The usual staplers H having wire feed devices I are mounted on the cross bar J above the plane of the sprocket wheels.

The blank to be made comprises the cleats K, binding wires L and M, and veneer N, the cleats being step-mitered at their ends. 10 Because of this construction of the box blank, the devices for spacing and gaging the materials, and feeding the blanks through the machine, are as follows: The link belts O are provided with teeth o, on 15 the upper surfaces of the links thereof, which teeth are adapted to engage the bottoms or lower edges of the cleats of the blanks. The link belts travel on the sprockets E and F, are parallel, and move endwise 20 of the direction of the cleats of the blanks. With this construction the cleats move along the longitudinal guides P, until they engage teeth o, after which the cleats are guided by the links of the said belts. The upper 25 portions of these link belts are supported by guides Q, whereby they are prevented from sagging under the load of the cleats and veneer from which the blanks are made. The guides P are provided with overhanging 30 flanges p, which latter bear upon the tops of the blanks as the latter pass under the staplers. Thus the serrated or toothed links of the belts O engage the bottoms or 35 the lower edges of the cleats, for the purpose of moving the same endwise, and during this time the upward thrust of the link belts is sustained by the flanges p, whereby the blanks are prevented from rising and thereby becoming disengaged from the teeth of 40 the chains, as shown more clearly in Fig. 3. With this construction a spacing block R exemplifies spacing means separate from the feeding mechanism and arranged to be positioned at the rear end of a cleat, wherever 45 said rear end may occur relative to the feeding mechanism. The spacing block having its position thus determined by the location of a cleat, serves to maintain the desired spaced relation between said cleat and the 50 next following cleat. The illustrative blocks, being separate from the feeding mechanism, are adapted to be withdrawn readily from the spaces between the cleats, but are preferred to be in spacing position 55 at some point in advance of the wire attaching point, and to remain in place between the cleats and to be fed thereby to substantially the wire-attaching point, so as to insure proper relative positioning of the parts 60 so long as necessary. Thus endless traveling members are provided, having teeth for engaging the bottom or longitudinal surfaces of the cleats, whereby the latter are caused to travel along the guides of the machine. The spacing blocks R are provided

with recesses r above the teeth o, in the manner shown more clearly in Fig. 3. In this way the said teeth are adapted to enter the wood of the cleats of the blanks, but do not engage the spacing blocks R, by reason of the provision of the recesses r. In other words, these recesses r permit the spacing blocks to travel along without engaging the teeth of the endless link belts. It will also be seen that the specific blocks R have 75 upstanding portions r' which separate or space the edges of the sheets N of the blank, whereby the folding of the blank is facilitated and lapped corners of the desired character are provided for the illustrative 80 box.

With the construction thus shown the cleats will be moved forward until they engage the link belts, and some provision is necessary for insuring a correct positioning of the cleats at the opposite edges of the blanks. By this I mean that some provision must be made whereby the cleats at one side edge of the blanks will be positioned exactly opposite the cleats at the other side thereof. For 90 this reason I provide a horizontal shaft S mounted in bearings s on the guides P. The said shaft has its ends provided with vertically disposed arms s', as shown more clearly in Fig. 2. The guides P are provided with 95 slots p', and the arms s' have their upper ends provided with pins or fingers s² that work back and forth in these slots. These pins are provided with cam grooves s³ adapted to engage the cams s⁴ on the guides. It 100 will be seen that these pins or fingers s² are controlled by the springs s⁵, which springs tend to keep the ends of the said pins or fingers in the position shown in Fig. 7. Normally, therefore, these pins or fingers s², 105 which serve as positioning devices or gages, project into the path of the cleats. The operator will take a pair of cleats and place the same in the guides P, one in each guide, and shift the same forward against the pins or fingers s². Then a pair of the spacing blocks R is placed in position, one block in 110 one guide and the other block in the other guide, and each block against the end of the cleat. Then two more cleats are placed in the guides, with their ends against the said blocks. The remainder of the cleats and blocks are then placed in position, in said guides, and the veneer is then placed thereon. When the materials for a single blank 115 are thus placed in position the same are shoved forward against the pins or fingers s², which latter then move forward until they engage the cams s⁴. The engagement of the cams s⁴ with the cam grooves s³ causes 120 the lateral withdrawal of the pins or fingers s² from the path of the cleats, so that the latter are then free to engage the teeth on the endless link belts. The operator continues 125 to exert a forward pressure on the veneer 130

and cleats of the blank until the same are all fully picked up or engaged by the teeth on the link belts. Of course, after the cleats are all picked up by the toothed or serrated links of the belts they are then held firmly in their relative positions, and will be secured together in such manner as to form a perfect blank. The pins or fingers s^2 are, therefore, in the nature of traveling stops for correctly assembling the cleats and sheets of veneer for a single blank before the same are finally pushed forward and picked up by the feeding mechanism. As the pin or finger s^2 at one side of the machine is exactly opposite the pin or finger s^2 at the other side thereof, it follows that the cleats at one side of the blank will be exactly opposite those at the other side thereof, and a perfect blank will thus be made. Thus the pins s^2 are also in the nature of gaging devices for correctly positioning the parts of the blanks. The arms s' are held in their normal positions by the springs s^6 which connect them with the guides P , in the manner shown in Fig. 1. Thus the operator must overcome the tension of these springs s^6 , when the materials for the blank are shoved forward to the feeding mechanism consisting of the toothed links of the chains o . When the last pair of cleats passes the pins or fingers s^2 the latter then spring back into place, and are thus made ready to receive the materials for another blank. The pins s^2 are devices which are used in producing proper relative arrangement of the cleats, which travel only a distance with the parts of the blank, and which are then withdrawn to do the same thing over again. It will be understood, of course, that the springs s^6 draw the arms s' backward as soon as the pins or fingers s^2 are disengaged from the cleats. These pins or fingers do not, however, reenter the path of the cleats—that is to say, do not reenter the guides P , until after the last cleats have passed and have been picked up by the feeding mechanism. But nevertheless, these pins s^2 are gaging or positioning devices which operate on each blank that goes through the machine, as distinguished from a spacing or gaging device which only operates on or engages one out of every so many blanks.

Thus I provide a machine for making wire bound box blanks in which the cleats travel along fixed guides, and in which means are provided for spacing the cleats of each blank apart endwise, as well as for engaging the cleats and moving the same longitudinally of the said guides. The guides and endless traveling members are all adjustable laterally, whereby box blanks of different widths can be made by one and the same machine. With my invention the cleats are spaced apart endwise by loose spacing blocks, and the cleats are moved

longitudinally of the fixed guides by means of endless traveling members which have teeth or projections that engage the cleats laterally—that is to say, which engage the sides of the cleats, preferably the lower sides thereof. In this way endless traveling members are provided for feeding or moving the cleats along the guides. It is obvious, of course, that such endless traveling link belts can be arranged to travel in either vertical or horizontal planes and that the same can be provided with means for engaging either the sides or the bottoms of the cleats, as may be found necessary or desirable, so far as the broader purposes of my invention are concerned. The distance between the spacing blocks, as illustrated, can be varied to accommodate cleats of different lengths, without stopping the machine. With the construction illustrated, however, no adjustment is necessary, inasmuch as loose spacing blocks R are employed for spacing the cleats apart endwise. With this arrangement the feeding operation will be the same, regardless of whether the cleats are long or short. Thus with the arrangement shown no adjustment of the machine is necessary when the length of the cleats is changed or varied for boxes of different sizes.

The mechanism, it will be seen, insures having the spaces between the ends of the cleats at one side directly opposite the similar spaces at the other side. In other words, the fingers s^2 intercept each blank and position the parts thereof, the interception occurring before or in advance of the gripping action of the toothed feeding chains or link belts, the result being that the spacing at opposite sides is correct. The feed mechanism, consisting of the link belts with teeth, is non-spacing in character, and by this is meant that this feed mechanism is not capable of positioning or causing the spacing of the cleats. Hence the cleats must be positioned before they encounter said feed mechanism, and this is done by the said positioning device or finger. Of course, though, this device may be used in different ways, and for other purposes, without departing from the spirit of my invention. I do not, therefore, limit myself to the exact construction shown and described.

As will be apparent to those skilled in the art, the spacing means exemplified by a block R has its position determined by the rear end of a cleat; and in the specific illustrative machine there is no such connection between a spacing block at one side of a blank, and the corresponding spacing block at the other side of the blank, as would of itself determine a proper alignment of the cleats transversely of the blank. In other words, if the pair of cleats for the initial side section of a blank were not in proper

alinement this condition would not be remedied by the illustrative spacing blocks, which would simply be inserted or positioned one at the rear of each of said initial 5 cleats to maintain the spaced relation between such rear end and the next following cleat. Therefore it is important, in employing such spacing means separate from the feeding mechanism and located by the 10 cleats themselves, that a preliminary positioning operation be performed, as by the illustrative gages s^2 , which shall insure the proper alinement of the initial cleats transversely of the intended blank. After this 15 initial positioning operation which properly locates the initial cleats, the independent spacing means exemplified by the blocks R will then serve to maintain the proper spaced relation between said initial cleats 20 and the next following cleats, so that the latter shall be also maintained in desired transverse alinement.

With further respect to the feeding and spacing mechanism comprising the blocks R, 25 chains O and ratchet devices, it will be seen that, in the illustrative machine shown in the drawings, the cleats are propelled by an individual feeding connection for each cleat, whereby one cleat does not necessarily push 30 the other. Furthermore, the spacing means of said mechanism may be independent of and separate from the feeding means, as previously explained; but I do not limit myself to this independence of the spacing and 35 feeding means, so far as spacing members are concerned which are operable either closer together or farther apart without necessarily stopping the machine. The spacing blocks R form portions of said feeding and spacing 40 mechanism, and they are relatively movable to vary the space between them while the machine is running, except for their engagement with the cleats. In other words, these blocks R, during the assembly of the cleats, 45 have no fixed connection between them, and are capable of movement toward and away from each other while in operation, but are held in spaced relation by the cleats, whereby the blocks space the cleats and the cleats 50 space the blocks. Without cleats, the said blocks would be free to come together, as they are pressed forward; but when spaced by the cleats said blocks are held in proper relation to each other. Moreover, it will be 55 seen that the cleats may be propelled forward, as illustrated, by pressure which does not involve any lateral thrust on the cleats in the horizontal plane thereof. In this way the cleats have no tendency toward horizontal 60 displacement or deviation from straight paths below the staplers. Moreover, the teeth o on the chains contribute to hold the cleats in spaced relation before they are wired together, and thus the blocks R depend 65 on the cleats to hold them in spaced

relation. Thus, and with the arrangement shown, the mechanism involving the chains O feeds the cleats and sheets in spaced relation, and the intermittently advanced sections of the blank are successively wired together by the staplers. In this way, the immediate result of the stapling operation is a box blank composed of a series of separate sections which are unconnected except by the wires. In the illustrative mode of operation 70 described with reference to the specific machine shown in the drawings, the spacing blocks R may be retained in position between cleats even after the blank is completed, but when said spacing blocks have 75 been removed the blank then becomes freely flexible to be folded into box form.

What I claim as my invention is:

1. In a machine for making wire bound box blanks, the combination of guides for the cleats, endless traveling members provided with teeth for engaging horizontal surfaces of the cleats, loose spacing blocks interposed between the ends of the cleats, whereby the cleats of each blank are spaced apart endwise, means operating to position the cleats before they reach the said teeth and mounted to move a distance with the cleats about an axis below the path of travel of the materials, and devices for stapling 90 binding wires to the veneer and cleats of the blanks.

2. In a machine for making wire bound box blanks, the combination of parallel guides for the cleats, loose spacing blocks for separating the cleats, whereby the cleats of each blank are spaced apart endwise, endless traveling members provided with teeth adapted to engage longitudinal traveling surfaces of the said cleats, said endless traveling members and cleats being parallel, whereby the cleats of each blank are moved 100 forward by reason of their engagement with the said traveling members, means for positioning the cleats before they engage said members, movable a distance with the cleats, about an axis below the path of travel of the materials, whereby the ends of the cleats in one guide are sure to be even with the ends of the corresponding cleats in the other 105 guide, and a plurality of staplers having provisions for stapling the binding wires to the upper surface of the blanks.

3. In a machine for making wire bound box blanks, the combination of parallel guides for the cleats, whereby the cleats of each blank are arranged to travel forward in a plurality of parallel rows, loose spacing blocks for separating the cleats endwise, endless traveling members having teeth or projections for engaging longitudinal surfaces of the cleats, mechanism for operating said endless traveling members to feed the cleats forward, mechanism for insuring a correct 110 positioning of the members of one row of 115

120 staples below the staplers, and a plurality of staples having a correct position in each row of staples. 125

cleats relative to those of the other row of cleats, before said cleats are engaged by said endless traveling members, mounted to travel a distance with the said cleats, about an axis below the cleats, and devices for stapling binding wires to the upper surface of the blanks.

4. In a machine for making wire bound box blanks, the combination of means for spacing the cleats apart endwise, consisting of loose spacing blocks disposed between the opposing ends of the cleats, whereby the cleats alternate with spacing blocks in a plurality of longitudinally traveling rows, mechanism for insuring a correct positioning of the cleats and blocks of one row relative to those of another row and movable a distance with the cleats and blocks, and devices for stapling the binding wires to the veneer and cleats of the blanks, said mechanism comprising two oppositely arranged devices for engaging the ends of the cleats, which cleat-engaging devices are movable into and out of the path of the cleats, and disposed in position to bear against the sides of the cleats while the latter are moving along.

5. In a machine for making wire bound box blanks, the combination of means for engaging longitudinal surfaces of the cleats, comprising endless traveling members provided with teeth or projections for engaging the cleats, said teeth or projections adapted to penetrate into the wood of the cleats, whereby the said members are operative to move the cleats endwise in a plurality of longitudinally traveling rows, mechanism for insuring a correct positioning of the cleats before they are engaged by the teeth of said members, mounted to travel a distance in engagement with the ends of the cleats, about an axis below the cleats, and devices for stapling binding wires to the veneer and cleats of the blanks.

6. A wire bound box blank machine comprising devices whereby the blanks are given a step by step feeding motion, means for applying the parallel binding wires, mechanism for gaging or positioning parts of the blanks before the said wires are applied thereto, and before the said parts are engaged by said devices, said mechanism including a pair of gaging or positioning fingers movable a distance with the parts of the blank, means for withdrawing the fingers, means for returning the fingers to normal or starting position, and constantly acting means tending to project the fingers into the path of said certain parts, held in restraint by direct engagement of said fingers with the moving materials, while the fingers are waiting to move into operative position.

7. A wire bound box blank machine comprising devices whereby the blanks are given a step by step feeding motion, means for

applying the parallel binding wires, mechanism for gaging or positioning parts of the blanks before the said wires are applied thereto, and before the said parts are engaged by said devices, said mechanism and devices permitting variation in the size of said parts to vary the length of the blanks, said mechanism including a pair of gaging or positioning fingers held under restraint by direct engagement thereof with the moving materials, while waiting to move into operative position, which fingers when in operative position travel a distance with said parts, cam portions connected with said fingers, and stationary projections that strike said cams to throw the fingers out.

8. A wire bound box blank machine comprising devices whereby the blanks are given a step by step feeding motion, means for applying the parallel binding wires, mechanism for gaging or positioning parts of the blanks before the said wires are applied thereto, and before the said parts are engaged by said devices, said mechanism and devices permitting variation in the size of said parts to vary the length of the blanks, said mechanism comprising a pair of gaging or positioning devices held stationary by direct sliding contact with the moving materials, while waiting to operate, which gaging devices enter the paths of travel of the cleats of the blank and travel a distance therewith, and means whereby the movement of said gaging devices operates to withdraw them from said paths whereby said gaging devices permit the cleats to pass.

9. A wire bound box blank machine comprising devices whereby the blanks are given a step by step feeding motion, means for applying the parallel binding wires, mechanism for gaging or positioning parts of the blanks before the said wires are applied thereto, and before the said parts are engaged by said devices, said mechanism and devices permitting variation in the size of said parts to vary the length of the blanks, said mechanism including a pair of gaging or positioning fingers held stationary by direct sliding contact with the moving materials, while waiting to operate and movable toward and away from each other to intercept and release the cleats of the blank, means for mounting said fingers to travel a distance with the cleats, means for withdrawing the fingers, and means for returning the fingers to normal position.

10. A wire bound box blank machine comprising devices whereby the blanks are given a step by step feeding motion, means for applying the parallel binding wires, mechanism for gaging or positioning parts of the blanks before the said wires are applied thereto, and before the said parts are engaged by said device, said mechanism and devices permitting variations in the size of

said parts to vary the length of the blanks, said mechanism including a pair of gaging or positioning fingers held stationary by direct sliding contact with the moving materials, while waiting to operate, which fingers travel a distance with the cleats of the blank, and means for returning the fingers in contact with the outer sides of the cleats.

11. A wire bound box blank machine comprising means for applying the parallel binding wires, mechanism for gaging or positioning the parts of the blank before the said wires are applied, said mechanism including a pair of gaging or positioning fingers held stationary by direct sliding contact with the moving materials, while waiting to operate and movable toward and away from each other to move into and out of the path of certain parts of the blank, means for mounting said fingers to travel a distance with the said parts, means for withdrawing the said fingers laterally of the path of travel of said parts, and means for returning the said fingers to normal position.

12. A wire bound box blank machine comprising devices whereby the blanks are given a step by step feeding motion, means for applying the parallel binding wires, mechanism for gaging or positioning parts of the blanks before the said wires are applied thereto, and before the said parts are engaged by said devices, said mechanism including a pair of gaging or positioning fingers held stationary by direct sliding contact with the moving materials while waiting to operate, arranged at opposite sides of the machine and adapted to project in front of the ends of the cleats, means whereby said fingers move a distance with the cleats, means for withdrawing the fingers at the end of their travel, to permit the cleats to pass, and means for returning the fingers in contact with the sides of the cleats.

13. A wire bound box blank machine comprising devices whereby the blanks are given a step by step feeding motion, means for applying the parallel binding wires, mechanism for gaging or positioning parts of the blanks before the said wires are applied thereto, and before the said parts are engaged by said devices, said mechanism including a pair of gaging or positioning devices held stationary by direct sliding contact with the moving materials while waiting to operate and disposed at opposite sides of the machine adjacent the paths of travel of the cleats, said gaging devices provided with fingers for engaging the ends of the cleats, said fingers mounted to move a distance with the cleats, then pull out to permit the cleats to pass, and then return to normal position.

14. A wire bound box blank machine comprising devices whereby the blanks are given

a step by step feeding motion, means for applying the parallel binding wires, mechanism for gaging or positioning parts of the blanks before the said wires are applied thereto, and before the said parts are engaged by said devices, said mechanism comprising a pair of gaging or positioning fingers, springs for projecting said fingers into the path of travel of certain parts of the blank to gage the positions thereof, said springs being held under tension by direct engagement of said fingers with the moving materials, said fingers traveling a distance with the said parts, and means whereby said fingers withdraw from said path to permit the parts in rear thereof to pass under the said means for applying the binding wires.

15. In a wire bound box blank machine, staplers for stapling the binding wires to the blanks, means including a pair of parallel link belts with teeth for engaging the longitudinal surfaces of all the cleats for producing a step by step feeding motion of the blanks under and away from the said staplers, and mechanism in front of the staplers for insuring a proper delivery of parts of the blanks to said link belts, said mechanism including a pair of gaging or positioning fingers movable into and out of the path of travel of certain parts of the blanks and held out of the path of travel of said parts by direct frictional contact therewith, the said fingers when in operative position moving a distance with the said parts.

16. In a wire bound box blank machine, staplers for stapling the binding wires to the blanks, cleat guides, feeding means for advancing the cleats step by step along said guides, and mechanism in front of the staplers for insuring a proper delivery of the cleats to said feeding means, said mechanism including a pair of gaging or positioning fingers, held out of the path of travel of the cleats by direct frictional contact therewith, movable into the paths of travel of the cleats, then movable a short distance with the cleats along said guides, then movable out of the path of the cleats laterally thereof, and then returnable to normal position.

17. In a wire bound box blank machine, a pair of cleat guides, feeding means for producing a step by step movement of the cleats along the guides, staplers for securing the binding wires to the blanks, and mechanism in front of the staplers for insuring a proper delivery of parts of the blanks to the said staplers and feeding means, said mechanism including a gaging or positioning finger for each guide, means for causing the fingers to enter the guides, held under restraint by direct engagement of the fingers with the sides of the cleats, said fingers when in operative position traveling a distance along said guides, means for auto-

matically withdrawing the fingers from the guides, and means for returning the fingers to normal position.

18. In a wire bound box blank machine, guides for the cleats, feeding means for producing a step by step movement of the cleats and other parts of the blanks along said guides, staplers for securing the binding wires to the blank, and mechanism for properly positioning the cleats before they are delivered to said staplers, said mechanism including two gaging portions which are held out of operative position by direct engagement with the sides of the cleats, and which automatically enter the guides to position the cleats and move a short distance therewith, each said portion intervening only between the ends of the blanks.

19. In a wire bound box blank machine, a pair of parallel link belts having teeth that engage the longitudinal surfaces of the cleats to feed the latter step by step, and mechanism for insuring proper positioning of the materials before the same are engaged by said teeth, said mechanism including two gaging portions that intercept and position the cleats, move a short distance therewith, withdraw from the path of the cleats, and finally return to inoperative position, being held in said position by direct frictional contact with the moving cleats, each said portion intervening only between the ends of the blanks.

20. A wire bound box blank machine comprising a wiring device, a step-by-step operated feed device for moving the blanks, and mechanism for positioning parts of the blanks before said parts are wired together, including a gaging portion which is movable into and out of the path of said parts, held out of gaging position by direct engagement with said parts, and disengaging the said parts immediately before engagement thereof with said feed device.

21. A wire bound box blank machine comprising a wiring device, a step-by-step operated feed device for moving the blanks, mechanism for positioning parts of the blanks before said parts are wired together, and for disengaging the said parts immediately before engagement thereof with said feed device, said mechanism including a pair of gaging or positioning fingers which automatically enter behind the cleats, to intercept the next cleats, held out of gaging position by direct engagement with the cleats, and said fingers being movable a short distance with said cleats and then movable out of the path thereof.

22. A wire bound box blank machine comprising a wiring device, a step-by-step operated feed device for moving the blanks, and mechanism for positioning parts of the blanks before said parts are wired together, and for disengaging the said parts imme-

ately before engagement thereof with said feed device, said mechanism including a pair of gaging portions which are movable into and out of the path of the blanks, and which are also movable a short distance therewith, together with means for automatically returning said portions to inoperative position.

23. A wire bound box blank machine comprising a wiring device, a step-by-step operated feed device for moving the blanks, and mechanism for positioning parts of the blanks before said parts are wired together, and for disengaging the said parts immediately before engagement thereof with said feed device, said mechanism including a pair of gaging portions movable a short distance with parts of the blanks, means for automatically withdrawing said gaging portions laterally of the path of travel of said parts, and means for automatically returning said gaging portions to inoperative position.

24. A box blank machine provided with mechanism for positioning parts of the blanks, said mechanism comprising a pair of gaging or positioning fingers movable toward and away from each other, into and out of the path of travel of said parts and held in inoperative position by direct engagement with said parts, means for mounting said fingers to travel a distance with the said parts, means for withdrawing said fingers laterally of the path of travel of said parts, and means for returning said fingers to waiting position.

25. A box blank machine comprising intermittently operated means for feeding the blanks, means for wiring the blanks, and mechanism for positioning the cleats before they are wired, said mechanism including gaging devices which are held in retracted or inoperative position by direct contact therewith of the moving cleats, and which engage the ends of the cleats and travel only a short distance therewith.

26. A box blank machine provided with intermittently operated feed mechanism for moving the blanks, wiring mechanism, and positioning mechanism including gaging portions movable with and by the forward movements of the parts of the blanks, before said parts reach said feed mechanism, means for withdrawing the gaging portions, said gaging portions being held in retracted position by direct frictional contact with the moving parts positioned thereby.

27. A wire bound box blank machine comprising devices for feeding the blank materials, mechanism for wiring the materials together, and elements for relatively positioning said materials, by direct engagement therewith, having a limited amount of travel with said materials while in the path thereof, and held out of said path by direct contact with the moving materials positioned thereby, together with constantly acting

- means for holding said elements against said materials, said machine permitting variations in the length of the blanks by simply varying the size of said materials.
- 5 28. A wire bound box blank machine comprising devices for feeding the blank materials, mechanism for wiring the materials together, and elements for relatively positioning said materials, by direct engagement therewith, having a limited amount of travel with said materials while in the path thereof, and held out of said path inoperative position by direct contact with the moving materials positioned thereby, said machine 10 permitting variations in the size of said materials to vary the length of the blanks, and a spring for forcing said elements against said materials and into the path thereof.
- 15 29. A wire bound box blank machine comprising devices for feeding the blank materials, mechanism for wiring the materials together, and elements for relatively positioning said materials, by direct engagement therewith, having a limited amount of travel with said materials while in the path thereof, and held out of said path by direct contact with the moving materials positioned thereby, together with constantly acting means for holding said elements against said materials, said machine permitting variations in the length of the blanks by simply varying the size of said materials, and means for spacing some of said materials before passing said elements.
- 20 30. A wire bound box blank machine comprising devices for feeding the blank materials, mechanism for wiring the materials together, and elements for relatively positioning said materials, by direct engagement therewith, having a limited amount of travel with said materials while in the path thereof, and held out of said path by direct contact with the moving materials positioned thereby, together with constantly acting means for holding said elements against said materials, said machine permitting variations in the length of the blanks by simply varying the size of said materials and a guide for the materials, said elements movable transversely of said guide, and also in a direction parallel therewith.
- 25 31. A wire bound box blank machine comprising devices for feeding the blank materials, mechanism for wiring the materials together, and elements for relatively positioning said materials, by direct engagement therewith, having a limited amount of travel with said materials while in the path thereof, and held out of said path by direct contact with the moving materials positioned thereby, together with constantly acting means for holding said elements against said materials, said machine permitting variations in the length of the blanks by simply varying the size of said materials, said devices including endless link belts having teeth which engage said materials.
- 30 32. A wire bound box blank machine comprising devices for feeding the blank materials, including longitudinal cleats and transverse strips of veneer, mechanism for wiring the materials together, and elements for relatively positioning said materials, by direct engagement therewith, having a limited amount of travel with said materials while in the path thereof, and held out of said path by direct contact with the moving materials positioned thereby, together with constantly acting means for holding said elements against said materials, said machine permitting variations in the length of the blanks by simply varying the size of said materials, and means for spacing the cleats before passing said elements.
- 35 33. A wire bound box blank machine comprising means for producing a step by step advancement of the blank materials, staplers for wiring the materials together, and mechanism for properly positioning the materials, before the wiring together thereof, comprising a finger operable into and out of the path of said materials, movable a fixed distance therewith, whereby said finger has the same extent of forward motion for different lengths of blank, and automatic means for returning said finger in the opposite direction.
- 38 34. A wire bound box blank machine comprising means for producing a step by step advancement of the blank materials, staplers for wiring the materials together, mechanism for properly positioning the materials, before the wiring together thereof, comprising a finger operable into and out of the path of said materials, movable a fixed distance therewith, whereby said finger has the same extent of motion for different lengths of blank, and means for keeping said finger pressed against the moving materials while waiting to move into operative position.
- 40 35. A wire bound box blank machine comprising means for producing a step by step advancement of the blank materials, staplers for wiring the materials together, mechanism for properly positioning the materials before the wiring together thereof, comprising a finger operable into and out of the path of said materials, movable a fixed distance therewith, by the forward pressure of the materials thereon, whereby said finger has the same extent of motion for different lengths of blank, and separate means for forming the spaces between the ends of the cleats.
- 45 36. A wire bound box blank machine comprising means for producing a step by step

advancement of the blank materials, staplers for wiring the materials together, mechanism for properly positioning the materials before the wiring together thereof, comprising a finger operable into and out of the path of said materials, movable a fixed distance therewith, whereby said finger has the same extent of motion for different lengths of blank, means for keeping said finger 5 pressed against the moving materials while waiting to move into operative position, and separate means for forming the spaces between the ends of the cleats.

37. A wire bound box blank machine comprising guides for the cleats, whereby said cleats are held end to end in parallel rows, mechanism for producing a step by step feeding motion of the cleats and other materials along said guides, means engaging and 10 traveling a distance with the cleats in the path thereof, about an axis below said guides, to properly position the cleats, and mechanism for wiring the materials together, said axis extending transversely of 15 the direction of travel of the cleats.

38. A wire bound box blank machine comprising guides for the cleats, whereby said cleats are held end to end in parallel rows, mechanism for producing a step by step 20 feeding motion of the cleats and other materials along said guides, means engaging and traveling a distance with the cleats in the path thereof, about an axis below said guides, to properly position the cleats, and mechanism for wiring the materials together, said means intercepting only the 25 cleats that form the ends of the blanks, said axis extending transversely of the direction of travel of the cleats.

40. 39. A machine for producing foldable box blanks by wiring together separate box sides each comprising separate side sheet material and individual cleats,—which comprises 30 wire-attaching mechanism; parallel cleat guiding means; coöperating cleat gages, one for each cleat guiding means, located intermediate the receiving end of the guiding means 35 and the wire-attaching point, to engage the advance ends of the cleats for the initial box side of a blank, preparatory to a positive feed of said cleats to the wire-attaching point; movable supporting means for said 40 gages comprising a shaft mounted transversely of the machine, supports for the respective gages fixed upon said shaft, said gages being held thereby in desired alignment transversely of the machine to insure 45 correct alignment of said cleat-ends, while permitting said gages to move in unison about the axis of said shaft and lengthwise the guiding means to maintain transverse alignment of said cleat-ends during part of 50

their travel, said gages being so arranged as 55 to be automatically withdrawn from the cleat paths, during said movement lengthwise the guiding means, to permit the cleats to pass; cleat-feeding means for each guiding means, comprising an endless chain having 60 spurs upon the faces of its links positively gripping the cleats laterally while leaving the cleat-ends substantially disengaged, said cleat-feeding means having their receiving ends located between the initial 65 cleat-end-engaging positions of said gages and the wire-attaching point, to receive the cleats in predetermined transverse alignment and to feed the same positively to the wire-attaching point; and a cleat spacer separate 70 from said feeding means and independent of said gages, to be inserted in the cleat path at the rear end of each said initial cleat, to maintain the desired space between 75 said rear end and the advance end of the next following cleat, said cleat spacer being fed forward in spacing position by said next following cleat to the wire-attaching point and being arranged to be subsequently withdrawn from the cleat path for use in another spacing operation.

40. A machine for producing foldable box blanks by wiring together separate box sides each comprising separate side sheet material and individual cleats,—which comprises 95 wire-attaching mechanism; parallel cleat guiding means; coöperating cleat gages, one for each cleat guiding means, located intermediate the receiving end of the guiding means and the wire-attaching point, to engage the advance ends of the cleats for the initial box side of a blank, preparatory to a positive feed of said cleats to the wire-attaching point; movable supporting means for said gages maintaining them in desired 100 alignment transversely of the machine to insure correct alignment of said cleat-ends, while permitting said gages to move in unison lengthwise the guiding means to maintain transverse alignment of said cleat-ends during part of their travel, and to be automatically withdrawn from the cleat paths to permit the cleats to pass; positive 105 cleat-feeding means for each guiding means, comprising an endless chain having means for positively gripping the cleats laterally, said cleat-feeding means having their receiving ends located between the initial cleat-end-engaging positions of said gages and the wire-attaching point, to receive the 110 cleats in predetermined transverse alignment and to feed the same positively to the wire-attaching point; and a cleat spacer separate from said feeding means and independent of said gages, to be inserted in the 115 cleat path at the rear end of each said initial cleat, to maintain the desired space between said rear end and the advance end

of the next following cleat, said cleat spacer being fed forward by said next following cleat to the wire-attaching point and being arranged to be subsequently withdrawn from the cleat path.

41. A machine for producing foldable box blanks by wiring together separate box sides each comprising separate side sheet material and individual cleats,—which comprises wire-attaching mechanism, a plurality of cleat guiding means; coöperating cleat gages, one for each cleat guiding means, located intermediate the receiving end of the guiding means and the wire-attaching point, to engage the advance ends of the cleats for the initial box side of a blank, preparatory to a wire-attaching operation; movable supporting means for said gages for maintaining them in desired alinement transversely of the machine to insure correct alinement of said cleat-ends, while permitting said gages to move in unison lengthwise the guiding means to maintain transverse alinement of said cleat-ends during part of their travel, and to be automatically withdrawn from the cleat paths to permit the cleats to pass; cleat-feeding means positively gripping the cleats laterally and located to receive the cleats in predetermined transverse alinement and to feed the same positively in relation to the wire-attaching point, each cleat-feeding means being sufficiently extensive to engage and feed concurrently a plurality of cleats; and a cleat spacer separate from said feeding means and independent of said gages, to be inserted in the cleat path at the rear end of each said initial cleat, to maintain the desired space between said rear end and the advance end of the next following cleat, said cleat spacer being fed forward by said next following cleat to the wire-attaching point.

42. A machine for producing foldable box blanks by wiring together separate box sides each comprising separate side sheet material and individual cleats,—which comprises wire-attaching mechanism, a plurality of cleat guiding means; coöperating cleat gages, one for each cleat guiding means, located intermediate the receiving end of the guiding means and the wire-attaching point, to engage the advance ends of the cleats for the initial box side of a blank, preparatory to a positive feed of said cleats relative to the wire-attaching point; movable supporting means for said gages to maintain them in desired alinement transversely of the machine to insure correct alinement of said cleat-ends, while permitting said gages to move in unison lengthwise the guiding means to maintain transverse alinement of said cleat-ends during part of their travel, and to be automatically withdrawn from the cleat paths to permit the cleats to pass; cleat-feeding means for each guiding means,

arranged to engage and feed concurrently a plurality of cleats; and a cleat spacer separate from said feeding means, to be inserted at the rear end of each said initial cleat, to maintain the desired space between said rear end and the advance end of the next following cleat.

43. A machine for producing foldable box blanks by wiring together separate box sides each comprising separate side sheet material and individual cleats,—which comprises wire-attaching mechanism; cleat supporting means at the front of the machine arranged to receive cleats in preliminary assembly preparatory to a positive feed; so positively acting cleat-feeding means having their receiving ends located between said cleat-supporting means and the wire-attaching point, to receive cleats after preliminary assembly, said cleat-feeding means being sufficiently extensive to engage and feed concurrently separate cleats for a plurality of side sections of the blank; coöperating cleat gages located in front of the receiving ends of said cleat-feeding means to engage cleats for the initial side section of a blank, as a part of the preliminary assembly; movable supporting means for said gages arranged to maintain them in desired alinement transversely of the machine to insure correct transverse alinement of said cleats while permitting said gages to move in unison lengthwise the cleats to maintain transverse alinement of said cleats during part of their travel; and cleat spacers separate from said feeding means and independent of said gages, so arranged as to maintain desired spaces between the rear ends of said initial cleats and the advance ends of the next following cleats and to be fed with said cleats by said feeding mechanism.

44. A machine for producing foldable box blanks by wiring together separate box sides each comprising separate side sheet material and individual cleats,—which comprises wire-attaching mechanism; coöperating cleat gages alined transversely of the machine to engage cleats for the initial box side of the blank, preparatory to feed of such cleats to the wire-attaching point, said gages being movable into and along and out of the cleat paths in front of the wire attaching point; cleat-feeding means sufficiently extensive to engage and feed concurrently separate cleats for a plurality of side sections; and cleat spacers arranged to be positioned and fed by the cleats and having means for feeding side sheet material.

45. A machine for producing foldable box blanks by wiring together separate box sides each comprising separate side sheet material and individual cleats, which comprises wire-attaching mechanism; a plurality of cleat guiding means; coöperating cleat gages arranged to be movable into and out of the

cleat paths and aligned transversely of the machine to engage the cleats for the initial box side of a blank, preparatory to the feed of said cleats relative to the wire-
5 attaching means; cleat feeding means arranged to receive cleats from said gages and to feed concurrently a plurality of longitudinally aligned cleats; and cleat spacers separate from said feeding means, arranged
10 to be fed between said initial cleats and following cleats.

46. A machine for producing foldable box blanks by wiring together separate box sides each comprising separate side sheet material
15 and individual cleats,—which comprises wire-attaching mechanism; a plurality of cleat guiding means; coöperating cleat gages aligned transversely of the machine and arranged to engage cleats for the initial box
20 side of a blank, preparatory to feed of said cleats relative to the wire-attaching means, said gages being so arranged as to be movable into and along and out of the cleat paths in front of the wire-attaching point;
25 cleat feeding means sufficiently extensive to engage and feed concurrently separate cleats for a plurality of side sections; and cleat spacers to maintain spaces between the said initial cleats and following cleats.

47. A machine for producing foldable box blanks by wiring together separate box sides each comprising separate side sheet material and individual cleats,—which comprises wire-attaching mechanism; coöperating
25 cleat gaging means aligned transversely of the machine and located in front of the wire-attaching point; means for moving said cleat gaging means into and out of the cleat paths; cleat feeding means arranged to engage and feed concurrently a plurality of longitudinally aligned separate cleats having end
40 portions relatively positioned to permit them to mate when folded.

48. A machine for producing foldable box blanks by wiring together separate box sides each comprising separate side sheet material and individual cleats,—which comprises wire-attaching mechanism; cleat supporting means at the front of the machine arranged to receive cleats in preliminary assembly preparatory to a position feed; coöperating cleat gaging means aligned transversely of the machine and located to receive cleats in said preliminary assembly; cleat feeding means between said cleat supporting and gaging means and the wire-attaching point, to receive cleats after preliminary assembly, said cleat feeding means being arranged to engage and feed concurrently a plurality of longitudinally aligned cleats; and cleat spacing devices structurally separate and independent of the machine and arranged to be introduced into the cleat
55 paths together with the cleats and to be re-

moved from the cleat paths together with the cleats.

49. A machine for producing foldable box blanks by wiring together separate box sides each comprising separate side sheet material
70 and individual cleats,—which comprises wire-attaching mechanism; cleat guides; gaging means located intermediate the ends of said guides for transversely alining corresponding cleats in said guides, said gaging means being reciprocable lengthwise the guides to accompany forward movement of the cleats through a fraction of their travel and then to return to initial position; automatic means for moving the gaging means
75 into and out of the cleat paths; and cleat feeding means arranged to engage and feed concurrently a plurality of longitudinally aligned cleats.

50. A machine for producing foldable box blanks by wiring together separate box sides each comprising separate side sheet material and individual cleats,—which comprises wire-attaching mechanism; cleat supporting means at the front of the machine to receive
80 cleats in preliminary assembly preparatory to a position feed; preliminary gaging means located proximate said cleat supporting means and arranged to aline cleats transversely of the machine in said preliminary assembly; and cleat-feeding means between the cleat supporting means and the wire-attaching point, arranged to engage and feed concurrently a plurality of longitudinally aligned separate cleats having end
85 portions relatively positioned to permit them to mate when folded.

51. A machine for producing foldable box blanks by wiring together separate box sides each comprising separate side sheet material
90 and individual cleats,—which comprises wire-attaching mechanism; cleat guides; gaging means located intermediate the ends of said guides for transversely alining corresponding cleats in said guides, said gaging means being reciprocable lengthwise the guides to accompany forward movement of the cleats through a fraction of their travel and then to return to initial position; automatic cam means arranged to operate during
95 forward movement of the cleats and said gaging means for moving the gaging means out of the cleat paths; and cleat-feeding means arranged to engage and feed concurrently a plurality of longitudinally aligned
100 cleats.

52. A machine for producing foldable box blanks by wiring together separate box sides each comprising separate side sheet material and individual cleats,—which comprises
105 wire-attaching mechanism; cleat supporting means at the front of the machine to receive cleats in preliminary assembly preparatory to a position feed; preliminary operating gaging means in front of the wire attaching
110

point, arranged to assist in alining cleats transversely of the machine in such preliminary assembly; spacing devices arranged to be positioned respectively at and by the rear ends of the cleats so alined and to gage the advance ends of the next following cleats; a second set of spacing devices arranged to be positioned by and at the rear ends of said next following cleats to gage the advance ends and aline a third set of cleats; and a third set of spacing devices adapted to be positioned by and at the rear ends respectively of said third set of cleats, to gage the advance ends of the fourth set of cleats; and means for feeding said cleats so positioned together with said spacing devices, toward the wire-attaching point.

53. A machine for producing foldable box blanks by wiring together separate box sides each comprising separate side sheet material and individual cleats,—which comprises wire-attaching means; cleat guides; preliminarily operating gaging means arranged to assist in alining transversely of the machine the corresponding cleats at opposite sides of a blank section, said gaging means being arranged to project sufficiently into the cleat paths to arrest said initial cleats with their advance ends in desired transverse alinement, and to be made inoperative by forcing said cleats forward; and a plurality of spacing devices associated with each guide and arranged to be adjusted in succession, the first having its adjusted position determined by the rear end of said initial cleat and serving to position the advance end of the second cleat of the blank, the second spacing device having its adjusted position determined by the rear end of said second cleat and serving to position the advance end of the third cleat of the blank, and so on; and means for feeding said cleats and spacing devices toward the wire-attaching point.

54. A machine for producing foldable box blanks by wiring together separate box sides each comprising separate side sheet material and individual cleats,—comprising parallel cleat guides; feeding and spacing mechanism including a plurality of belts disposed parallel with said guides, provided with an individual feed connection for each cleat, by positive engagement therewith in a manner to avoid lateral thrust thereon in the horizontal plane thereof, and portions of which mechanism serve as spacing members for separating the cleats at intervals in the length of the blank, being arranged to be interposed between and held apart by the cleats; means for causing intermittent movement of said belts along said guides, to give said spacing members and the cleats and side sheets a step by step feeding motion; and wire attaching means for successively wiring together the intermittently advanced sections of the blank; said feeding and spacing

mechanism having said spacing portions thereof capable of relative movement while said belts are running, except as between any two or more spacing members held temporarily in desired relation by the cleats, thereby being operable with cleats of different lengths without stopping the machine.

55. A machine for producing foldable box blanks by wiring together separate box sides each comprising separate side sheet material and individual cleats,—comprising parallel cleat guides; feeding and spacing mechanism including a plurality of belts disposed parallel with said guides, provided with an individual feed connection for each cleat, by positive engagement therewith in a manner to avoid lateral thrust thereon in the horizontal plane thereof, and portions of which mechanism serve as spacing members for separating the cleats at intervals in the length of the blank, being arranged to be interposed between and held apart by the cleats; means for causing intermittent movement of said belts along said guides, to give said spacing members and the cleats and side sheets a step by step feeding motion; and staplers for successively wiring together the intermittently advanced sections of the blank; said feeding and spacing mechanism having said spacing portions thereof capable of relative movement while said belts are running, except as between any two or more spacing members held temporarily in fixed relation by the cleats, thereby being operable with cleats of different lengths without stopping the machine, said belts consisting of endless sprocket chains disposed in parallel vertical planes, and said members, while in spacing position, being disposed in a horizontal plane above the tops of said chains, supported thereon.

56. A machine for producing foldable box blanks by wiring together separate box sides each comprising separate side sheet material and individual cleats,—comprising parallel cleat guides; feeding and spacing mechanism including a plurality of belts disposed parallel with said guides, provided with an individual feed connection for each cleat, by positive engagement therewith in a manner to avoid lateral thrust thereon in the horizontal plane thereof, and portions of which mechanism serve as spacing members for separating the cleats at intervals in the length of the blank, being arranged to be interposed between and held apart by the cleats; means for causing intermittent movement of said belts along said guides to give said spacing members and the cleats and side sheets a step by step feeding motion; and wire-attaching mechanism for successively wiring together the intermittently advanced sections of the blank; said feeding and spacing mechanism having said spacing portions thereof capable of relative movement while

said belts are running, except as between any two or more spacing members held temporarily in fixed relation by the cleats, thereby being operable with cleats of different 5 lengths without stopping the machine, said chains being of a length to engage the sections of an entire blank in advance of the wiring operation, and serving to propel the assembled sections toward said wire-attaching mechanism.

57. A machine for producing foldable box blanks by wiring together separate box sides each comprising separate side sheet material and individual cleats,—comprising parallel 15 link belts; means on said belts for engaging and propelling the cleats; guides for the

cleats; spacers carried on said belts, having provision to prevent engagement of the spacers with said engaging means, whereby each spacer is slidably carried on one said 26 belt; means for causing feeding movement of said belts; and mechanism for successively wiring together the cleats held in relative positions by said spacers and for also fastening the sheets to the cleats. 25

Signed by me at St. Joseph, Michigan, this 8 day of October 1909.
